UNITED STATES PATENT OFFICE.

CAMILLUS DUNBAR, OF GLENWOOD, AND JAMES A. RECTOR, OF LANCASTER, MISSOURI.

WEATHER-BOARDING GAGE.

SPECIFICATION forming part of Letters Patent No. 328,661, dated October 20, 1885.

Application filed July 10, 1885. Serial No. 171,168. (No model.)

To all whom it may concern:

Be it known that we, CAMILLUS DUNBAR and JAMES A. RECTOR, citizens of the United States of America, residing, respectively, at 5 Glenwood and Lancaster, both in the county of Schuyler and State of Missouri, have invented certain new and useful Improvements in Weather-Boarding Gages; and we do hereby declare the following to be a full, clear, and 10 exact description of the invention, such as will enable others skilled in the art to which it appertains to make and use the same, reference being had to the accompanying drawings, and to letters or figures of reference 15 marked thereon, which form a part of this specification.

This invention relates to a novel construction of weather-boarding gages; and it consists, essentially, in constructing the gage with 20 a frame provided with a handle-grasp, by which the device can be readily held while being used, and with slotted portions through which an adjustable gage-bar of peculiar construction may slide, said bar having a notched 25 or serrated face which engages with the slotted frame, and is thereby securely held in position, and with an index or graduated scale to indicate the position to which the bar is adjusted; in connecting to one face of 30 the frame corrugated or crimped spring-plate, by means of which the gage is securely held to the work, and the device is adapted for use on boards of varying thickness; in providing the adjustable gage-bar at its upper 35 end with a head or board rest, and in attaching thereto a reversible spring having at one end an offset to hold the board in position, all as hereinbefore described.

In the accompanying drawings, Figure 1 40 represents a perspective view of our improved gage; Fig. 2, a side elevation thereof, and Fig. 3 a bottom plan view.

Heretofore gages of this character have usually been constructed of several separate parts 45 connected together by thumb-screws, which in use are liable to become loose and impair the operativeness of the device, and usually the gage-bar has been slotted and its adjustment secured by means of a thumb-screw, 50 which, as compared with our arrangement, is a clumsy and slow method of adjustment.

The frame of our improved weather-boarding gage is constructed in two parts, A B, as shown. The portion A has at each end inwardly-extending slotted flanges C D, and intermediately thereof an outwardly-extending angular portion, E, to which the lower end of the curved portion B is riveted or otherwise secured, the upper end being also secured to the part A by a rivet, screw, clamp, or other 55 suitable means. By forming the part B of curved shape, such as shown, a handle is thereby formed by means of which the tool can be readily grasped and held by the hand while in use, while the other hand of the operator is free to operate the gage-bar, to be presently described.

F represents an elongated slot formed in the lower end of the handle B, which registers with the slot G in the flange D on the 60 lower end of the part A of the frame.

H represents a slot in the upper face of the handle, of corresponding or nearly corresponding size to the size of the gage-bar, which may be of square, round, or any other 65 desired or suitable shape in cross-section, so as to form a guide therefor. This slot is out of alignment with the slots F and G.

I represents the spring gage-bar, which, at 70 its end, has an angularly-shaped head or board rest, J, its lower portion being of right-angled form or offset, as shown, so as to insure sufficient room being left between it and the curved portion of the handle to permit of the insertion therein of the operator's hand, so as 75 to afford a firm grasp of the tool. The lower end of the gage-bar has on one or more faces thereof graduating-marks or a scale, K, corresponding with the notches or serrations L, formed in one face or edge thereof. These 80 notches or serrations engage with one edge of the slots F and G in the lower part of the tool, and thus hold it securely in any position to which it may be adjusted.

To secure the adjustment of the gage-bar to 85 any required position all that is necessary is for the operator to press the lower end of the bar aside, so as to release the notches from engagement with the slotted edges, and then either push or pull the bar up or down, as it 90 may be desired to lengthen or shorten the extent of projection beyond the upper end of the

frame of the upper end of the gage-bar. Upon the desired position of adjustment being reached the sidewise pressure upon the lower end of the gage-bar is released, and the notches 5 immediately and automatically engage with the lower slotted portions of the frame and rigidly hold the bar in its adjusted position.

M represents a corrugated spring, formed of steel or other suitable metal or material, rigidly attached at its lower end to the angular portion E of the part A of the frame, the free end of said spring extending upward beyond the portion E. This spring in operation is passed between the two boards below, the board being placed in position so as to clamp the gage to its work.

N represents a reversible spring, of steel or other suitable metal or material, pivotally connected at O to the gage-bar head J. For the purpose of holding the board in place, the short end P of this spring extends at a right angle and downwardly, as shown, and the spring can be turned upon its pivot so as to bring either the shorter or longer end into operative position, as it may be desired to grip boards of different widths or thicknesses.

It is designed to construct the entire tool of steel or other suitable metal, as thereby it can be made very strong and of slight bulk, and is not subject to warping by the action of the weather or to destruction by being roughly handled, as would be the case were it made partly of wood. By constructing the spring M of corrugated form the gage is held more securely in position and is prevented from slipping, as the corrugations afford firmer gripping-faces than is possible where plane-faced springs are employed.

We are aware that gages have already been constructed with plane-faced spring-arms for the purpose of holding the gage and boards in position, and such we do not claim.

Having thus described our invention, what we claim is—

45 1. In a weather-boarding gage, a two-part metallic frame having a bow-shaped portion to form a hand-grasp, and slots at each end and intermediate thereof to receive and guide a gage-bar jointly with a gage-bar having at or near its lower end notches or serrations to engage one of the slots in the frame, and at its upper end a board-holding arm, substantially as set forth.

50 2. A weather-boarding gage having a corrugated metallic spring rigidly attached at its

lower end to the inner face of the frame, and extending upwardly therefrom, for the purpose of holding the gage to its work, substantially as set forth.

3. A weather-boarding gage having pivotally connected thereto a reversible metallic spring for holding the boards in place, said spring having at one end a right-angled and downwardly-extending offset, as and for the purpose set forth.

65

4. A weather-boarding gage having a corrugated metallic spring rigidly attached at its lower end to the frame, and extending upwardly therefrom, for the purpose of holding the gage to its work, and a reversible metallic spring for holding the boards in place, the latter spring having at one end a right-angled and downwardly-extending offset, as and for the purpose set forth.

70

5. In a weather-boarding gage, a gage-bar-guiding frame having at its upper end and at or near its center right-angled portions provided with slots to form guides for the gage-bar, and at its lower portion an elongated slot extending partly out of alignment with the slots in the upper part of the frame, jointly with a gage-bar having notches or serrations adapted to engage with the lower slotted portion of the frame, substantially as set forth.

75

6. In a weather-boarding gage, a gage-bar-guiding frame having at its upper end and at or near its center right-angled portions provided with slots to form guides for the gage-bar, and at its lower portion an elongated slot extending partly out of alignment with the slots in the upper part of the frame, jointly with a gage-bar having at or near its lower end an offset notched portion adapted to engage the slotted elongated slot in the lower portion of the frame, substantially as set forth.

80

7. The combination, with a gage-bar-guiding frame having angularly-extending slotted portions, of a gage-bar having at its upper end a transversely and downwardly extending head, and a board-gripping spring pivoted thereto, and having at one end a right-angled and downwardly-extending offset, substantially as set forth.

85

In testimony whereof we affix our signatures in presence of two witnesses.

CAMILLUS DUNBAR.
